UNITED STATES PATENT OFFICE.

JOHN CHRISTOPHER EVANS, OF AKRON, OHIO, ASSIGNOR TO THE AMERICAN RUBBER & TIRE COMPANY, OF AKRON, OHIO, A CORPORATION OF OHIO.

DESIGN FOR FOOTWEAR.

60,785.

Specification for Design. Patented Apr. 11, 1922.

Application filed September 23, 1921. Serial No. 502,832. Term of patent 7 years.

To all whom it may concern:

Be it known that I, JOHN CHRISTOPHER EVANS, a citizen of the United States, residing at Akron, in the county of Summit and State of Ohio, have invented a new, original, and ornamental Design for Footwear, as shown in the accompanying drawing and described in the following specification.

I claim:

The ornamental design for footwear as shown.

JOHN CHRISTOPHER EVANS.
